CLAIM

The ornamental design for a checkout counter, as
shown and described.

DESCRIPTION

FIG. 1 is a perspective view of a checkout counter
showing my new design;

FIG. 2 is an enlarged top plan view thereof;

FIG. 3 is an enlarged front elevational view thereof;

FIG. 4 is an enlarged rear elevational view thereof;

FIG. 5 is an enlarged right end elevational view thereof;

FIG. 6 is an enlarged left end elevational view thereof.

The partial showing of the circular apertures in FIGS.
1, 3 and 5 are understood to repeat uniformly throughout
the defined areas.
